R. J. STARR

CIGARETTE MAKING MACHINE

Filed March 9, 1923

INVENTOR
ROBERT J. STARR.

BY *Feckenstochbaugh Co.*
ATTN:

UNITED STATES PATENT OFFICE.

ROBERT JULIUS STARR, OF BRIERCREST, SASKATCHEWAN, CANADA.

CIGARETTE-MAKING MACHINE.

Application filed March 9, 1923. Serial No. 623,891.

To all whom it may concern:

Be it known that I, ROBERT JULIUS STARR, a citizen of the United States of America, and resident of Briercrest, in the Province 5 of Saskatchewan and Dominion of Canada, have invented certain new and useful Improvements in Cigarette-Making Machines, of which the following is a specification.

This invention relates to improvements 10 in cigarette making machines and the objects of the invention are to provide a simply constructed and most inexpensive cigarette machine of this kind that can be easily carried about and expeditiously and 15 efficiently operated.

With these and other objects in view, the invention consists essentially in the construction and arrangement of parts as described in the present specification and 20 illustrated by the accompanying drawings that form part of the same.

Referring to the drawings, in which like characters of reference indicate corresponding parts in each figure,

25 Figure 1 is a perspective view of the cigarette making machine.

Figure 2 is a vertical section of the machine open.

Figure 3 is a longitudinal section.

30 Figure 4 is a section through the machine closed.

In the drawings, A is a cigarette making machine as a whole, comprising a channel-shaped body or casing 10, of a suitable 35 length to accommodate a cigarette provided with cam-shaped ends 11 and 12 having a greater periphery than the ends of the channel member 10 and so placed as to extend beyond the channel member 10 at all points, 40 connected by transversely extending bar members 13, 14, 15, 16 and 17 placed as shown in the drawings.

18 is a second and operative channel-shaped member pivotally mounted on the 45 bar 13 between the ends 11 and 12 and provided with an outer edge bent outward to grip and support a flat split plate 19 adjustably mounted thereon and formed with ends extending slightly beyond the cam-shaped ends 11 and 12 of the channel member 10 and designed to receive there-through a ribbon of flexible material 20. This ribbon 20 of flexible material constitutes the means, in combination with the 50 casing, for making the cigarette. The cam-shaped ends 11 and 12 are narrower toward

the swinging member 19 thus forming a shoulder projecting slightly beyond the bar member 16 so that when the operative channel member 18 is closed the projecting 60 ends of 19 come in contact with the shoulders on the cam-shaped ends and hold the channel member 18 a predetermined distance from the bar. 21 is a brake or friction member pivotally mounted on bar member 65 15 and designed to apply friction to the ribbon member 20.

This opening between the plate 19 and bar 16 is for the purpose of allowing ribbon 20 to pass freely over the edge of 70 channel member 18 and bar member 16 without interference of that part of the ribbon that runs in one direction with that part of the ribbon running in the opposite direction, and for the further purpose of receiving 75 the cigarette paper in which the cigarette is to be rolled.

Furthermore, it is to be noted that the adjustable mounting of the plate 19 on the member 18 enables it to be so set on the bent 80 edge of the member 18 that a portion of the ribbon passing over the edge of the latter after having passed through the plate will contact with that portion of the ribbon passing over the bar member 16. 85

In other words, the split plate 19 may be either fixed on the member 18 as illustrated or it may be adjustably mounted thereon so that it can be moved to leave no opening between the ribbon portion passing over the 90 bent edge of the member 18 and over the bar member 16.

The ribbon 20 passes through the split plate 19 around the bent edge of 18 and into the chamber formed by 18 and 10, 95 passes out and over bar 16 and under bar 17 then over 21.

Between the bar member 13 and the bar member 14 there should be a space of approximately a quarter of an inch or such 100 other width as may be suitable to allow any waste tobacco that may work around the ends of the ribbon or otherwise find its way into the body chamber to escape out of the machine so as not to clog the mechanism in 105 its operations.

In making a cigarette the machine is held in the left hand with the left thumb under the split plate 19 and against the channel member 18 and the fingers of the left hand against brake 21. The channel member 18 is then turned away from the 110

channel member 10 so as to leave the machine open. The ribbon is pushed into the channel member 10 by the finger or any other suitable object and the required amount of tobacco spread evenly in the channel portion 10 on top of the ribbon. Channel member 18 is then closed. Both the extended ends of the split plate 19 strike the cam-shaped ends 11 and 12 leaving a sufficient opening between 18 and 19 for the ribbon 20 to pass freely. The ribbon 20 is then pulled first one way and then the other, thereby rolling the tobacco into proper shape for the cigarette. During this process the brake 21 is applied to the ribbon with such force as may be necessary to roll the tobacco hard or leave it comparatively loose as may be desired. When the tobacco has been rolled sufficiently the ribbon is drawn away from the operator till the end next the operator extends just sufficiently far through the split plate 19 to permit of its being easily grasped to pull it back again. The non-gummed edge of a gummed cigarette paper is then inserted between the split plate 19 and the bar member 16 with the gummed side of the paper turned towards the operator. The ribbon 20 is then pulled toward the operator, which action causes the cigarette paper to be drawn into the machine until just the gummed edge of the paper protrudes above the split plate 19. The gum is then moistened and the ribbon member 20 pulled toward the operator until the cigarette is completely rolled and made. The lid member 18 is then opened to allow the cigarette as made to come out.

The ends of the ribbon member 20 may be equipped with ornamental metal coverings to prevent tearing or other damage to the ends of the ribbon member 20.

As many changes could be made in the above construction and many apparently widely different embodiments of my invention within the scope of the claims constructed without departing from the spirit or scope thereof, it is intended that all matter contained in the accompanying specifications and drawings shall be interpreted as illustrative and not in a limiting sense.

What I claim as my invention is:

1. A cigarette making device comprising a channel shaped body member provided with extended end portions connected by a plurality of rods and having an opening to one side, a lid member pivotally mounted on one of said rods and adapted to provide a space between the lid member and the body, a split plate clamped adjustably to the lid member to act as ribbon guide and stop, a brake member pivotally mounted on one of the rods connecting said end

portions, a ribbon member of flexible material arranged to pass through the split plate into the chamber formed by the body member and the lid member, then out and over the body member, then under one of the before mentioned rods and over the brake member and operated by a pull upon the ribbon, substantially as set forth.

2. A cigarette making device comprising a channel shaped main body member having ends secured thereto which extend outside of the channel and connected thereto by means of a plurality of rods, a channel shaped lid member mounted pivotally on one of the said rods in such manner that the openings of the body member and the lid member are facing one another, thereby forming an operating chamber with an opening between the said main body member and said lid member along the pivotal line, a split plate ribbon guide member with extended end portions to act as stops adjustably mounted on the upper turned back edge of the lid member, a ribbon member passing through said split plate guide then through an opening between the upper edges of the main body member and lid member into the operating chamber forming a loop therein, then out through the same opening over the upper edge of the main body member, under or over one of the before mentioned rods and operated by pulling the ribbon member in either direction, substantially as set forth.

3. A cigarette making device comprising a channel shaped body member having ends secured thereto by a plurality of rods, a lid member of channel shape, the upper flange being bent outwardly and carrying a ribbon guide member with stop portions secured thereto, the lower flange having a bead for one of the mentioned rods to pass through whereby the lid member is pivoted some distance from the adjacent edge of the body member, between the end portions of said body member, a brake member pivotally mounted on one of the before mentioned rods and operated by finger pressure, a non-elastic ribbon member of flexible material having finger pieces attached to its ends and arranged to pass through the guide portion and over or under one of the rods before mentioned and then over the brake member and operated by pulling the ribbon member in one direction or the other.

In witness whereof I have hereunto set my hand in the presence of two witnesses.

ROBERT JULIUS STARR.
